UNITED STATES PATENT OFFICE.

ALEXANDER W. MARR, OF CANTON, OHIO.

QUICK-ACTION JACK.

1,257,508.

Specification of Letters Patent. Patented Feb. 26, 1918.

Application filed August 10, 1917. Serial No. 185,586.

To all whom it may concern:

Be it known that I, ALEXANDER W. MARR, a citizen of the United States, residing at Canton, in the county of Stark and State of Ohio, have invented certain new and useful 5 Improvements in Quick-Action Jacks, of which the following is a specification.

This invention relates to new and useful improvements in quick-action jacks.

10 The principal object of the invention is to provide means in a double-ratchet jack whereby the user may speedily raise the lifting bar to the load before commencing to elevate it, and thereafter quickly lift the 15 load with a minimum amount of effort. Another object of the invention is to provide means in such a jack whereby, after the load is lowered sufficiently to remove the weight, the lifting bar will drop down of its own 20 accord.

Another object of the invention is to provide a quick-action jack which is not only compact, simple and durable in construction, but which may be readily operated.

25 Other important and incidental objects will be set forth in the following specification and particularly pointed out in the subjoined claims.

The preferred form of embodiment of my 30 invention is illustrated in the accompanying drawings, of which Figure 1 is a side elevational view of my improved jack. Fig. 2 is a front elevational view of said jack, showing the vertical opening for the foot-lift carried by the lifting bar revealed through said opening. Fig. 3 is a side elevational view of the upper portion of said jack, with the crank-control in its uppermost position. Fig. 4 is a side elevational 35 view of said jack, with the upper portion thereof broken away to reveal the lifting and control devices and showing the jack in an elevating position. And Fig. 5 is an elevational view of the right side of said jack.

40 Throughout the specification and drawings, similar reference characters denote corresponding parts.

In a detailed description of the preferred form of embodiment of my invention, the 50 numeral 1 designates a tubular standard mounted upon a base 2. Vertically movable within the standard 1 is a lifting bar 3, to the lower end of which a foot-lift 4 is preferably forged, for movement through a vertical opening in the front portion of said 55 jack as shown in Fig. 2. The base 2 is

preferably spot-welded onto the tubular standard 1, after the lifting bar 3 and foot-lift 4 have been assembled in the jack frame. Upon its upper end the lifting bar 3 carries 60 a concave head 5.

Formed along the front and rear sides of the lifting bar 3 is a longitudinal series of downwardly-pointed ratchet teeth 6 adapted to be engaged by a pair of upwardly-pointed 65 lifting pawls 7 pivotally supported within the following described frame construction provided on the upper part of the standard 1.

Preferably screwed to each side of the upper portion of the tubular standard 1 is a fan-shaped plate 8, to the lower middle portion of which there is pivotally secured, by a screw 9, a lever piece 10. These lever pieces straddle the standard 1, and support 75 between their inwardly converging outer ends a lever-handle receiving block 11.

Secured to each one of the lever pieces 10, one on each side of the screw 9, is a short shaft 12 upon which one of the lifting pawls 80 7 is loosely mounted. These two shafts 12 loosely extend through arcuate slots 13 provided in each of the plates 8 to allow them, and the pawls 7 which they carry, an up and down movement when the lever pieces 10 85 are given a vertical reciprocating movement by the user of the jack.

In order to cause the pointed ends of the lifting pawls 7 to engage the ratchet teeth 6 of the lifting bar 3 to raise it when the 90 jack lever is operated, the following construction is provided. Projecting outwardly from each pawl 7, near each end thereof, is a short cylinder 14 which contains a compression spring 15 that exerts its force to 95 maintain a plunger 16 in the path of a beveled cam extension 17 at right angles to, and integral with, a vertically movable slide 18. There are two of these slides 18, each comprising a flat bar containing a longitudinal slot 19 near each end thereof. (See 100 Figs. 1 and 4.)

Projecting loosely through each one of the slots 19 into the left side plate 8 near each side edge thereof, is a guiding screw 20. 105 (See Figs. 1 and 4.) These screws 20 guide the slides 18 through a vertical movement which brings their right-angled cam extensions 17 into engagement with the two upper spring-pressed plungers 16 movable in 110 the cylinders 14 of the pawls 7. Therefore, when the slides 18 have been raised to their

uppermost position, as shown in Fig. 4, the cam extensions 17 will be so placed with reference to the two upper plungers 16 that the latter will slidably engage them during the reciprocating movement of the pawls 7, to force the nose portions of the latter into engagement with the ratchet teeth 6 on the lifting bar 3. In other words, when the pawls are moved up and down by the lever pieces 10, the cam extensions 17 of the slides 18 will press against the plungers 16 with sufficient force to compress their springs 15. Since the outward movement of the plungers 16 is now limited by the extensions 17 of the slides 18, the compressed springs 15 will force the nose portions of the pawls 7 into engagement with their respective teeth 6 on the lifting bar 3.

When the operator of the jack gives the lever pieces 10 a reciprocating movement, the shafts 12 attached thereto will alternately carry the pawls 7 up and down. Furthermore, as the two upper plungers are now in engagement with the cam extensions 17 of the slides 18, the nose portion of a pawl 7, during its upward movement, will be in engagement with a tooth 6 on its respective side of the bar 3, to elevate the latter. During this upward movement of one pawl, the other one will be lowered by its respective shaft 12, with its nose portion riding idly over the teeth, and vice versa, as the operating lever is moved from one extreme position to the other. During each up and down movement of the operating lever, the bar 3 will be raised, since when one pawl is traveling downward, the other one is being carried upward in engagement with a tooth on its respective side of the bar 3.

For the purpose of enabling the lifting bar 3 to be raised to the load before commencing to elevate it, the slides 18 are drawn downward out of engagement with the two upper plungers 16 and into engagement with the two lower ones, by the following means:

Pivotedly secured to the tubular standard 1 below the side plate 8, by a screw 21, is a crank 22. The lower end of each slide 18 is preferably screwed to an outwardly projecting arm portion 23 of a vertically movable flat metallic member 24. The latter has an irregular hole 25 provided in its lower portion, through which the screw 21 extends. The contour of this hole is such that a cam pin 26 projecting inwardly from the crank 22 will engage the curved edge thereof when the crank is raised, to force the flat member 24, and the slides 18 attached thereto, upwardly to the position shown in Figs. 3 and 4, wherein the beveled cam extensions 17 of the slides will be in engagement with the two upper plungers 16 of the pawls 7, to hold the nose portions thereof in engagement with their respective ratchet teeth on

the bar 3. When in such position a downwardly projecting portion 27 of the plate 8 will have entered the recess between the arm portions 23 of the flat member 24 to firmly brace the latter. (See Figs. 1 and 3.)

When it is desired to lower the load, the crank 22 is turned downwardly to the position it occupies in Figs. 1 and 2, whereupon its cam pin 26 will draw down with it the flat member 24 attached thereto, thereby causing the beveled cam extensions 17 of the slides 18 to uncover the two upper plungers 16 and engage or cover the two lower ones.

As each pawl 7 is elevated to its extreme top position, its nose portion, which is beveled, will engage a roller member 28 journaled between the upper ends of the side plates 8. As the beveled nose portion of each pawl passes under a respective roller member 28, it will be forced thereby into engagement with a tooth 6 on its respective side of the lifting bar 3. If the weight of the load upon the lifting bar 3 is approximately twelve pounds or over, it will be sufficient to cause the nose portion of the pawl to be held in engagement with the tooth to sustain the descending load, since a load of that weight will be sufficient to hold the pawl and tooth in engagement against the pressure exerted on the lower end of the pawl by its lower compressed spring 15. And when that particular pawl has reached its extreme lower position, the nose portion of the other one will be forced, by its respective roller 28, into engagement with a tooth on its side of the lifting bar 3 to receive the weight of the load. At this point the lower spring 15 on the first named pawl, being compressed by the beveled extension 17, will exert its force against the lower end of said pawl to withdraw its upper end from engagement with the ratchet tooth 6, since the weight of the load has now been transferred to the other pawl.

It will now be seen that the nose portion of one pawl will remain in engagement with the tooth to sustain the weight of the load until the operating lever reaches one extreme position, whereupon the other pawl will be forced into engagement with a tooth on its respective side of the lifting bar 3 and let the weight down still further during the movement of the lever to its other extreme position, this alternate operation being continued until the lifting bar 3 is completely relieved of its load. After this point is reached and the lever is brought to a horizontal position, the lifting bar 3 will drop down to its normal position, since there is no weight upon it to hold its teeth 6 in engagement with the nose portions of the pawls. Likewise, when the lever is in a horizontal position and the extensions 17 of the slides 18 are over the lower plungers 16 of

the pawls 7, the lifting bar may be speedily lifted to its load-receiving position without operating said lever.

After the lifting bar 3 is thus raised to the axle of an automobile or other object to be raised, the crank 22 is turned to its uppermost position, thereby bringing the beveled slide extensions 17 into engagement with the two upper plungers 16 of the pawls 7. Accordingly, as before explained, the nose portions of the pawls will then be spring-pressed into continuous engagement with their respective teeth 6 on the lifting bar 3, to elevate the latter when the jack-operating lever is reciprocated by the user.

It will now be seen that the lifting bar of my improved jack may be readily and speedily raised to its load-receiving position without operating the lever, and that it will just as quickly descend to its normal position after it is relieved of the load. Furthermore, the lifting and lowering means I have provided are alternately operable on both sides of the lifting bar to insure a quick-action jack that is easy of operation and simple and durable in construction. To further insure efficiency of construction, I prefer that all parts of the jack be made of sheet-steel punchings except the lifting pawls, which are preferably made of drop forgings.

I do not wish to be limited to the details of construction and arrangement herein shown and described, and any changes or modifications may be made therein within the scope of the subjoined claims.

Having described my invention, I claim:

1. In a jack, the combination with a tubular standard, of a lifting bar having oppositely-disposed ratchet teeth thereon, slidably movable in said standard, a frame secured to the latter, a pair of oppositely-disposed lever elements fulcrumed to said frame, a pair of lifting pawls pivotally mounted between said lever elements, one on each side of the fulcruming means, and adapted to be given an alternate up and down movement by the lever elements, a spring on the upper portion of each pawl, and hand-controlled slidable means adapted to compress said springs to hold the nose portions of the pawls in engagement with the teeth on the lifting bar, whereby the latter may be raised when the lever elements are reciprocated.

2. In a jack, the combination with a tubular standard, of a lifting bar having oppositely-disposed ratchet teeth thereon, slidably movable in said standard, a frame secured to the upper portion of the latter, a pair of oppositely-disposed lever elements fulcrumed to said frame, a shaft connected between said lever elements on each side of the fulcruming means, a pawl loosely mounted on each shaft, adapted to be given an

up and down movement when the lever elements are reciprocated, a spring-pressed plunger projecting outwardly from the upper portion of each pawl, and crank-controlled means slidably secured to said standard below the frame, for movement into engagement with said plungers, to hold the nose portions of the pawls in engagement with the teeth on the lifting bar, whereby the latter may be raised when the lever elements are reciprocated.

3. In a jack, the combination with a tubular standard of a lifting bar having oppositely-disposed ratchet teeth thereon, slidably movable in said standard, a frame secured to the upper portion of the latter, a pair of oppositely-disposed lever elements fulcrumed to said frame, a shaft connected between said lever elements on each side of the fulcruming means, a pawl loosely mounted on each shaft, adapted to be given an up and down movement when the lever elements are reciprocated, a spring-pressed plunger projecting outwardly from each pawl, crank-controlled means slidably secured to said standard for vertical movement in said frame, and a pair of oppositely-disposed members carried by the slidable means adapted to be moved upwardly by the latter into engagement with said plungers to hold the nose portions of the pawls in engagement with the teeth on the lifting bar, whereby the latter may be raised when the lever elements are reciprocated.

4. In a jack, the combination with a tubular standard, of a lifting bar having oppositely-disposed ratchet teeth thereon, slidably movable in said standard, a frame secured to the upper portion thereof, a pair of pawls within said frame, a lever adapted to give said pawls an alternate up and down movement, a spring on the upper and the lower portion of each pawl, and slidable means adapted to alternately compress the upper and lower springs on said pawls, to hold their nose portions in engagement with the teeth on the lifting bar in the first instance and out of engagement therewith in the second instance.

5. In a jack, the combination with a tubular standard, of a lifting bar having oppositely-disposed ratchet teeth thereon, slidably movable in said standard, a frame secured to the upper portion of the latter, a pair of oppositely-disposed lever elements fulcrumed to said frame, a pair of lifting pawls pivotally mounted between said lever elements, one on each side of the fulcruming means, and adapted to be given an up and down movement by the lever elements, a spring-pressed plunger projecting outwardly from the top and bottom portion of each pawl, crank-controlled means slidably secured to said standard below the frame, and a pair of oppositely-disposed cam members

carried by the crank-controlled means, adapted to be moved by the latter into alternate engagement with the upper and lower plungers of the pawls, to hold their nose portions in engagement with the teeth on the lifting bar in the first instance and out of engagement therewith in the second instance.

6. In a jack, the combination with a tubular standard, of a lifting bar having oppositely-disposed ratchet teeth thereon, slidably movable in said standard, a frame secured to the upper portion thereof, a lever fulcrumed to said frame, a pawl carried by said lever on each side of its fulcruming means, an element in said frame to force the nose portion of a pawl into engagement with a tooth on the lifting bar when the pawl is carried to its extreme upper position by the lever, a spring on the lower end of said pawl, and cam means slidably secured to said standard, to compress said spring for the purpose of withdrawing the nose portion of said pawl from said tooth when the other pawl engages a tooth on its respective side of the lifting bar.

7. In a jack, the combination with a tubular standard, of a lifting bar having opposed series of ratchet teeth thereon, slid-

ingly mounted in said standard, a foot-lift secured to the lower portion of said bar and movable through an opening provided in said standard, two parallel supporting plates oppositely secured to the upper portion of said standard, a lever fulcrumed to each supporting plate, a shaft connected between said lever elements on each side of the fulcruming means and extending through arcuate slots provided in said plates, a pawl loosely mounted on each shaft, a spring-pressed plunger secured to the top and bottom portion of each pawl, a sliding slotted bar extending into said frame, one on each side of the standard, a right-angled cam member extending inwardly from each slotted bar, for alternate engagement with the top and bottom plungers on said pawls, and crank-controlled means slidably secured to said standard, for raising and lowering the slotted bars, to thereby force their cam members into alternate engagement with the upper and lower spring-pressed plungers on the pawls.

In testimony whereof I have hereunto set my hand this 8th day of August, 1917.

ALEXANDER W. MARR.
